ROLL PRESSURE ADJUSTER FOR
WRINGERSFred A. Conterman, Jamestown, N. Y., assignor to
Jamestown Metal Equipment Company, Inc.,
Jamestown, N. Y., a corporation of New York

Application July 31, 1943, Serial No. 496,900

3 Claims. (Cl. 68—262)

1

This invention relates to an improvement in washing machine wringers and particularly to a roll pressure adjuster.

It is common practice to provide wringers with manually operable adjusters by which to vary the roll pressure through adjustment of the pressure of a roll spring. However, it is considered advantageous to the operator of a wringer to be able to determine the roll pressure best suited for a given type of clothes without the need of running a trial piece through the rolls. To this end, the present invention has been developed and, in addition to providing necessary roll pressure adjusting means, provides, through an index structure, visual markings by which an operator may determine the roll pressure for which the adjuster has been set.

It is an object and advantage of the present invention to provide a roll adjuster that is freely operable, regardless of the roll pressure to which the adjuster has been previously set. It is also an object of the invention to provide an adjuster that discloses to the wringer operator the extent of roll pressure through suitable markings at any given position of adjustment. It is also an object of the invention to provide a roll pressure adjuster which may be changed from one marking to another and readily indicate to the operator, without trial, that the roll pressure is as desired for the type of clothes to be passed through the wringer.

Other objects and advantages of the invention will be more fully understood from a consideration of the following specification, taken in conjunction with the accompanying drawing; and in which

Fig. 1 is a fragmentary vertical sectional view of the top portion of a wringer in which one form of the invention is embodied;

Fig. 2 is a fragmentary front elevational view of the top portion of a wringer, parts being broken away to disclose certain structural details; and

Fig. 3 is a vertical sectional view taken substantially on the line 3—3 of Fig. 1.

Referring to the drawing, the reference numeral 10 is employed to generally designate a wringer in which one form of the invention is embodied. The wringer comprises a body portion 11 and a removable cover 12. For convenience of illustration, only that portion of the wringer is shown in the drawing that concerns the invention, and such disclosure includes an upper roll 13 mounted in end bearings 14, these bearings being located in channel guides 16. The

2

upper surface of each bearing 14 is engaged by an end portion 17 of a roll spring 18.

Directly over the central portion of the spring 18 the cover may be formed with a reinforced portion, such as indicated at 19, and this portion provided with an opening 21, the inner end of which is counterbored, as at 22. A substantially circular adjusting knob 23 is located exteriorly of the cover 12. This knob, as shown, is hollow and includes diametrically opposite apertures 24. Within the knob is a centered fixed hub 26 that is adapted to receive an internally threaded sleeve 27. The sleeve 27 is secured against rotation and displacement with respect to the hub in any suitable manner, as by a set screw 28. The lower end of this sleeve is formed with an annular rim or flange 29.

The central portion of the spring 18 is enclosed by a pair of straps 31 that include abutting, upstanding flanges 32. These flanges are formed with concentric, transverse openings through which a horizontally disposed rod 33 projects. A threaded shaft 34 projects into the sleeve 27. This shaft, at its lower end, terminates in a fork-like portion consisting of a pair of spaced apart, parallel arms 36. The lower end of each of these arms is arcuate, the lowermost portion of the arc contacting horizontal portions of the straps 31. Concentric openings in the arms 36 are of a size to receive rod 33. The rod is prevented from axial displacement with respect to straps 31 and arms 36 in any suitable manner, as by a struck-up portion 37 and cotter pin 38. Adjacent the counterbored area of the reinforced portion 19, the cover includes a pair of depending arms 39. These arms are spaced to receive an end of the rod 33, and serve as a guide for the rod during use of the adjuster.

The other end 41 of the rod 33 may be of reduced diameter to mount one end of an indexing pin 42. This pin projects upwardly through a suitable opening in the reinforced portion 19 of the cover into the interior of the knob 23. The pin is provided with suitable index markings, such as indicated at 43, these markings being visible through one or the other aperture 24 in the rim of the knob.

In assembling the structure, a bearing washer 44 is seated in the counterbored area 22 prior to projecting the sleeve 27 through the opening 21. When the sleeve has been properly installed, the rim or flange 29 thereof abuts washer 44. A further bearing washer 46 is mounted on the sleeve 27 and rests upon the upper surface of the reinforced portion 19. When the interior parts of the

structure have been assembled, the knob 23 is mounted by enclosing the upper portion of the sleeve 27 in the hub 26 and turning down the set screw 28.

The adjuster is operated by rotating knob 23 in one or the other direction, and such rotation feeds the shaft 34 upwardly or downwardly of the sleeve 27. If movement is in a direction to move the shaft downwardly, the arcuate ends of arms 36 apply pressure to depress the central portion of the spring 18 and thus increase the pressure of the spring ends 17 on the bearings 14 of the upper wringer roll 13. Since the top roll is in contact with the lower roll (not shown), pressure applied in this manner will be directly transmitted to the rolls. It will, of course, be appreciated that as the knob is rotated in a direction to feed the shaft 34 downwardly of the sleeve 27, pin 42 will also move downwardly and thus another marking 43 will be made visible through one of the apertures 24. For example, if it is desired to wring out clothes having inconsequential bulk, or to wring out heavier clothes to a greater degree of dryness, the knob 23 is rotated until the marking "3" is visible through one of the apertures 24. If a lesser degree of pressure of the rolls is desired, reverse rotation of the knob 23 will bring the marking "2" or "1" into registry with one of the openings 24. It will be clearly understood that a wringer operator may repeatedly obtain the same degree of roll pressure by rotating the knob 23 in one direction or the other until the desired marking registers with one of the openings 24.

Although applicant has shown and described his invention in its application to one type of wringer, it will be understood that variations of the structure may be made and are contemplated in the application of the structure to other wringers insofar as such variations are within the spirit and scope of the annexed claims.

Having thus set forth my invention what I claim as new and for which I desire protection by Letters Patent is:

1. In a wringer structure having a pair of adjustable rolls and a spring operable to exert a yielding pressure on said rolls, an adjusting device for said spring comprising a manually rotatable member mounted exteriorly of said struc-

ture and including means preventing displacement from a position of close proximity with said structure, a shaft having threaded engagement with said member and being axially movable by

5 rotation of said member, said shaft having operative engagement with said spring, and means preventing rotation of said shaft during axial movement thereof, said means mounting an indicator pin in a manner to be axially movable with and to the same extent said shaft is movable, said pin being capable of such movement with respect to said member as to give indication of the extent to which said shaft has actuated said roll pressure spring.

10 2. In a wringer structure having a pair of adjustable rolls and a spring operable to exert a yielding pressure on said rolls, an adjusting device for said spring comprising a hollow member mounted exteriorly of said structure for manual rotative movement, a shaft having a threaded end engaged with and enclosed by said member and being axially movable by rotation of said member, said shaft being joined to said spring in a manner to alter the tension thereof upon rotation of said member, and an indicator pin joined to and movable with said shaft, said pin projecting through said structure into the interior of said member, and markings on said pin registerable with an aperture in said member and serving to indicate the extent of pressure applied to said rolls.

15 3. In a wringer structure having a pair of adjustable rolls and a spring operable to exert a yielding pressure on said rolls, an adjusting device for said spring comprising a hollow rotatable member located exteriorly of said structure and having means preventing axial displacement with respect to said structure, a non-rotatable shaft projecting into and having a threaded end enclosed by said member, said shaft being joined to said spring and movable in the direction of its length by rotation of said member to alter the pressure of said rolls, and an indicator pin joined to and movable in the direction of movement of said shaft, said pin projecting into said member 20 and including markings adjacent the upper end registerable with an aperture in said member to indicate the pressure of said spring as applied to said rolls.

FRED A. CONTERMAN.
